UNITED STATES PATENT OFFICE.

MARTIN FEYBUSCH, OF SEA CLIFF, NEW YORK.

MACHINE FOR COATING LABELS AND SIMILAR ARTICLES WITH ADHESIVE.

1,279,311.

Specification of Letters Patent. Patented Sept. 17, 1918.

Application filed April 27, 1918. Serial No. 231,120.

To all whom it may concern:

Be it known that I, MARTIN FEYBUSCH, a citizen of the German Empire, and a resident of Sea Cliff, in the county of Nassau and State of New York, have invented certain new and useful Improvements in Machines for Coating Labels and Similar Articles with Adhesive, of which the following is a specification.

10 This invention relates to a machine of novel construction for providing the backs of labels and similar articles with an adhesive coating so that the labels are ready for attachment to their bases by means of 15 additional machines, with which the machine which forms the subject matter of the present invention, is designed to coöperate. The machine is also applicable to blanks that go to form paper boxes or parts 20 thereof, and to various other articles which are to be covered by an adhesive on one of their sides.

Briefly stated, the labels to be coated are stacked within an adjustable magazine, 25 their forward edges being brought into engagement with a rubber-covered roller, which is fixed. This roller serves not as a conveyer, but as an abutment, against which the labels are feathered out by means of a 30 series of feed tapes that constitute the bottom of the magazine. These feed tapes carry the successive bottom labels from under the fixed roller, and thus out of the magazine, to be engaged by a second series 35 of feed tapes which are operable either in conjunction with or independently of the first series. The second series of tapes in turn conveys the labels beneath a pair of conveying rollers and under a tension blade 40 to a paste applying roller, to the periphery of which they are held so as to become coated in the manner desired. The coated labels are stripped off this roller by a number of pick offs which turn the labels over and 45 conduct them, bottom upward, upon a conveyer belt. On this belt, they are subjected to the action of a number of pressure devices, that prevent them from peeling, and are carried to the labeling or other machine 50 for further treatment.

The invention consists in the various features of novelty, more fully pointed out in the specification and appended claims.

In the accompanying drawing:
Figure 1 is a left hand side elevation of 55 a coating machine embodying my invention:

Fig. 2, a right hand side elevation;
Fig. 3, a sectional plan on line 3—3 Fig. 1;
Fig. 4, a longitudinal section on line 4—4 60 Fig. 3;
Fig. 5, a cross section on line 5—5 Fig. 3;
Fig. 6, a section on line 6—6 Fig. 5;
Fig. 7, a section through the first tapes 65 operating clutch on line 7—7 Fig. 3;
Fig. 8, a section on line 8—8 Fig. 7;
Fig. 9, a front end elevation;
Fig. 10, a section through the main drive shaft clutch on line 10—10 Fig. 3;
Fig. 11, a section on line 11—11 Fig. 10; 70
Fig. 12, a section on line 12—12 Fig. 10;
Fig. 13, a view of the label before coating, and
Fig. 14, a view of the label after coating.

The machine frame 1 is provided at its 75 receiving or rear end with a magazine adapted to receive a stack of labels 2 to be gummed. This magazine is formed of a pair of side plates 3, mounted on a transverse shaft 4, along which they are adjustable so that the magazine may be set to labels of different widths. The bottom of the magazine is formed by a plurality of endless parallel feed belts or tapes 5 passing over front and rear feed rolls 6 and 7, and over 80 a suitable number of interposed idlers 8, one of which is flanged as at 9 to prevent a lateral displacement of the belts.

Above the forward ends of the upper belt-runs, there is mounted a non-rotatable 90 and normally fixed roller 10 which is covered by rubber jacket 11 and constitutes a cylindrical abutment for the labels. The shaft of this roller engages slotted arms 12 of the machine frame, along which it may 95 be vertically adjusted by coned screws 13, so that in this way, the clearance between the roller and the feed tapes may be set to labels of different thicknesses. In order to adapt the magazine for the reception of 100 labels which are longer than tapes 5, frame 1, is provided with a rearwardly extending longitudinally adjustable bracket 14 in which is mounted, a vertically adjustable shaft 15. On this shaft are mounted, a plurality of laterally adjustable clamps 16, carrying fingers

17, the front ends of which are adapted to rest upon one of the idlers 8 intermediate tapes 5, while their rear ends extend a considerable distance back of frame 1. When a pile of labels is placed upon the fingers, it will, by the forward portions of the feed tapes, be carried against the fixed cylindrical abutment 10 by means of which the labels are feathered out, in such a manner 5 that the forward edge of the pile is concaved and that the bottom label only will be fed out of the magazine by the feed tapes. The latter convey the label thus withdrawn from the magazine, upon a second set of 10 parallel belts or feed tapes 18 that advance it on its way toward the adhesive-receiving 15 means hereinafter referred to.

Tapes 18 pass over front feed roll 19 and a rear feed roll 20, the latter being 20 spaced a short distance beyond front roll 6, of the first set of tapes 5. Between rolls 19, 20 there are arranged, a number of idlers 21, one of which is flanged as at 22, while above the tapes are mounted in the 25 machine frame a number of pressure rolls 23, that serve to hold the labels to the tapes, during their travel along the latter. The object of providing two independent sets of feed tapes, is to permit either both sets to 30 be operated simultaneously (which is the normal condition) or the advance set 18 to be driven, while the rear set 5 is at rest. This stopping of the rear tapes should take place when the magazine is empty in order 35 to then prevent an abrasion of the rubber jacket 11 by the moving tapes 5 while the continued motion of the front tapes, will carry the train of labels last released to the gumming mechanism.

40 The means for driving the tapes are shown to be as follows: Power shaft 24 by coned pulley 25, belt 26, and coned pulley 27, drives a counter shaft 28. The latter, by pulley 29 and belt 30 drives a disk or 45 pulley 31, that may be coupled to the main drive shaft 32 by a clutch 33 (Figs. 10-12). The clutch may be opened or closed from the front of the machine by a handle 34 (Fig. 3) fast on an upright rock shaft 35 having 50 a finger 36, that engages a groove 37 in the hub of clutch 33.

Shaft 32 by chain drive 38, turns a stub shaft 39 having a long gear wheel 40, in which meshes a pinion 41 fast on feed roll 55 20 and also a pinion 42 of a clutch 43 (Figs. 6-8) adapted to be coupled to feed roll 6. Clutch 43 is operated from a rock shaft 44 by link 45, connecting rod 46, link 47, upright shaft 48 and finger 49, so that when 60 the clutch is thrown in, both sets of feed tapes are operated by pinions 41, 42 while when the clutch is thrown out by the turning of shaft 44, the front set only is operated by pinion 41.

65 Rock shaft 44 is also axially slid able and

is operatively connected to the clutch 33 of the main drive shaft 32 by a link 50, that engages shaft 35. The rock shaft is accessible to an operator stationed a distance back of the machine, so that by turning it he may 70 stop the rear feed only, while by sliding it he may stop the entire machine.

The front feed tapes 18 carry the labels toward and between a pair of intergeared feed rolls 51, 52 the lower one of which is 75 at 53, intergeared with shaft 32. From rolls 51, 52 the label passes underneath the lower edge of a tension blade 54 that serves to deflect the label toward the face of an adhesive applying roller 55, which is vertically adjustable and contacts with a paste receiving roller 56 dipping into a pan or receiver 57 containing an adhesive, such as glue or paste. Roller 56 is at 58 intergeared with feed roll 52 and is in turn at 59, intergeared with paste applying roller 55, so that rollers 55 and 56 turn in opposite directions.

To the front of the machine, there is fulcrumed at 60, a bracket 61 in which is journaled, a shaft 62 intergeared at 63 with roller 55 and arranged, a slight distance above the same so as to hold the labels against the latter. Over shaft 62, passes an endless conveyer belt 64 to which the labels are transferred with their backs up from 95 roller 55 by means of a number of pick-offs or strippers 65. The latter are secured to arms 67 that turn on a shaft 66 hung in bracket 61 in advance of shaft 62 and are made in the form of concaved jaws which 100 strip the labels off roller 55 after having remained in contact therewith for some time and turn them upward and backward in substantial concentricity to the periphery of shaft 62 which they partly encompass at the 105 turn of the conveyer belt. The conveyer belt 64 passes from shaft 62 over idlers 68, 69, 70, idler 69 being located at such a distance back of the machine as to carry the procession of gummed labels to the labeling or 110 other machine with which the present machine is designed to coöperate.

Bracket 61 carries above the upper run of belt 64, a number of shafts 71 from which depend hangers 72, in which are journaled 115 pressure rolls or disks 73. Hangers 72 are longitudinally adjustable along their shafts, so that the pressure rolls may be set over the labels as the latter are carried out of the machine, and prevent the same from peeling off 120 the conveyer.

By slackening a pair of clamp screws 74 bracket 61 together with its rollers and other adjuncts may be swung into a horizontal position (dotted lines Fig. 1) so as to carry 125 pick-offs 65 away from roller 55, and permit all the parts to be readily inspected, removed, cleaned or repaired.

The operation of the machine will be readily apparent from the foregoing description. 13

A stack of labels is placed in the magazine, and by the operation of the rear feed tapes 5 such stack is forced against the rubber jacket 11 of the fixed roll 10 which thus constitutes an abutment by means of which the labels are feathered out. The successive lowermost labels are transferred by the rear tapes 5, to the front tapes 18, which in turn convey them, beneath blade 54, to the face 10 of the paste applying roller 55 that covers their backs with the adhesive. Pick-offs 65 then strip the labels off roller 55, and turn them toward shaft 62, so that in this way, the labels are reversed and are transferred 15 "back upward" to the conveyer 64. The latter carries the labels to the labeling, box making or other machine for further treatment.

The machine is readily adjustable to labels 20 of various dimensions and configuration, feathers them out neatly, and carries them in a uniform procession to the paste applying means and thence to the conveyer. Should the operator of the machine with which the 25 present machine is intended to coöperate, see that the magazine is empty, he throws out clutch 43, by means of rock shaft 44, which is within his reach, and thus arrests the rear feed tapes while the remainder of 30 the machine retains its motion, so that the labels that have left the magazine will continue their travel toward the paste applying device and thence to the conveyer belt that keeps on moving and carries them to their 35 destination.

I claim:

1. A machine for coating labels or similar articles comprising a plurality of feed tapes, a paste applying roller, a shaft, an 40 endless conveyer belt engaging and turning at said shaft and a plurality of concaved pick-offs engaging the paste applying roller, and partly encompassing said conveyer belt at the turn thereof.
2. A machine for coating labels or similar articles comprising a frame, label feeding means carried thereby, a paste applying roller, an endless conveyer in proximity to said roller, a shaft engaged by said conveyer, and a plurality of concave pick-offs that engage the paste applying roller and partly encompass said shaft.
3. A machine for coating labels or similar articles comprising a rear set of feed tapes, a front set of feed tapes, separate means for operating said sets of tapes, a normally fixed cylindrical abutment mounted above

the rear set of tapes, a paste applying roller in advance of the front set of tapes, and a conveyer in proximity to said roller. 60

4. A machine for coating labels or similar articles comprising a rear set of feed tapes, a front set of feed tapes, pressure rolls above said second set, a pair of feed rolls in advance of said second set, a tension blade, a 65 paste applying roller coöperating therewith, an endless conveyer in proximity to said roller, a shaft engaged by said conveyer, and a plurality of concave pick-offs that engage said roller and partly encompass said shaft. 70

5. A machine of the character described, comprising a frame, label feeding means carried thereby, a paste applying roller, an endless conveyer in proximity thereto, a shaft engaged by said conveyer, a second 75 shaft hung in advance of the first named shaft, a plurality of arms turning on said last named shaft, and a plurality of concaved jaws carried by said arms and partly encompassing the first named shaft. 80

6. A machine of the character described, comprising a frame, label feeding means carried thereby, a paste applying roller, an endless conveyer in proximity thereto, a shaft extending across the conveyer, a plurality of hangers adjustable along said shaft, and pressure rolls journaled in the hangers and adapted to engage the conveyer. 85

7. A machine for coating labels and similar articles comprising a rear set of feed tapes, a first feed roll engaged thereby, a front set of feed tapes, a second feed roll engaged by the last named tapes, a drive shaft, intergeared with the second named 95 feed roll, and a clutch adapted to operatively connect said shaft to said first named feed roll. 90

8. A machine for coating labels and similar articles, comprising a rear set of feed 100 tapes, a first feed roll engaged thereby, a front set of feed tapes, a second feed roll engaged by the last named tapes, a power shaft, a drive shaft operatively connected to the second named feed roll, an axially 105 slidable rock shaft, a first clutch operable by a sliding movement of said rock shaft and adapted to operatively connect the drive shaft to the power shaft, and a second clutch operated by a turning movement of the rock 110 shaft and adapted to operatively connect said drive shaft to said first named feed roll.

MARTIN FEYBUSCH.
